UNITED STATES PATENT OFFICE.

WILLIAM H. ROBERTS, OF DAVENPORT CENTRE, NEW YORK.

FASTENING FOR BUTTER-PACKAGES.

SPECIFICATION forming part of Letters Patent No. 286,073, dated October 2, 1883.

Application filed August 2, 1883. (No model.)

To all whom it may concern:

Be it known that I, WILLIAM H. ROBERTS, of Davenport Centre, in the county of Delaware and State of New York, have invented 5 certain new and useful Improvements in Fastenings for Butter-Packages; and I do hereby declare that the following is a full, clear, and exact description of the invention, which will enable others skilled in the art to which it app-
10 pertains to make and use the same, reference being had to the accompanying drawings, which form a part of this specification, and in which—

Figure 1 is a perspective view of the upper portion of a butter-jar provided with my im-
15 proved fastening, and Fig. 2 is a perspective view of the fastening detached.

Similar letters of reference indicate corresponding parts in both the figures.

My invention has relation to fastenings for 20 the covers of butter-jars, and has for its object to provide a cover-fastening for the butter-
package for which Letters Patent No. 276,882 were granted to me on the 1st day of May, 1883; and it consists, to that end, in the improved 25 construction and combination of parts of the same, as hereinafter more fully described and claimed.

In the accompanying drawings, A represents 30 the butter-jar, B the cover, and C the annular flange against which the lower edge of the flanged cover rests. A piece of wire, D, is drawn tightly around the jar below the flange and the ends secured together in any suitable manner, and the wire, which is somewhat longer 35 than the circumference of the jar at that place, is passed through the annular eyes E of two screws, F, which are placed diametrically opposite to each other and turned, twisting the wire to form two upwardly-pointing twisted 40 shanks, G, for the eyes H, into which the screw-
eyes are linked. The screw-threaded shanks I of the screw-eyes pass through two perforations, J, one in each end of a flat yoke, K, which rests diametrically over the lid of the 45 jar, and are secured by means of two thumb-

nuts, L, which bear against the upper surface of the yoke, and serve to press the same down upon the cover when screwed down upon the screws. In this manner it will be seen that the wire ring may be placed around the jar, 50 the screws twisted to make it fit under the flange, and the yoke pressed down upon the lid by the thumb-nuts when the jar is to be closed, the flat eyes, resting against the sides of the flange or cover, preventing the screws 55 from turning when the thumb-nuts are turned, and when the jar is to be opened the nuts may be unscrewed, the yoke removed, when the cover may be raised.

Having thus described my invention, I claim 60 and desire to secure by Letters Patent of the United States—

1. A fastening for covers on jars, consisting of a wire having its ends secured together, adapted to fit under the flange at the top of the jar, 65 and twisted at diametrically-opposite places to form eyes, screw-eyes linked into the latter eyes, a yoke having perforations at each end for the passage of the screws of said screw-eyes, and thumb-nuts fitting upon the ends of 70 the screw-eyes, as and for the purpose shown and set forth.

2. The combination of a jar having a flange at its upper end, a cover fitting over the top of said jar, a wire ring fitting under the flange 75 of the jar and twisted at diametrically-opposite points, forming eyes, screw-eyes linked into said eyes, a yoke resting across the cover, and having perforations at the ends receiving the shanks of the screw-eyes, and thumb-nuts 80 fitting upon the ends of the screw-eyes, all constructed as and for the purpose shown and set forth.

In testimony that I claim the foregoing as my own I have hereunto affixed my signature 85 in presence of two witnesses.

WILLIAM H. ROBERTS.
